CLAIM

The ornamental design for a cable distribution elbow, as shown and described.

DESCRIPTION

FIG. 1 is a perspective view of the cable distribution elbow in accordance with the present invention;

FIG. 2 is a right elevational view of the cable distribution elbow of FIG. 1;

FIG. 3 is a left elevational view of the cable distribution elbow of FIG. 1;

FIG. 4 is a front elevational view of the cable distribution elbow of FIG. 1;

FIG. 5 is a rear elevational view of the cable distribution elbow of FIG. 1;

FIG. 6 is a top plan view of the cable distribution elbow of FIG. 1; and,

FIG. 7 is a bottom plan view of the cable distribution elbow of FIG. 1.

The broken lines depict portions of the cable distribution elbow that form no part of the claimed design.
